Genas Bliff, of Johnston. R. Island.

Letters Patent

The Schedule referred to in these Letters Patent, and making part of the same, containing a description in the words of the said Genas Bliff himself, of his improvement in the machine for Calendering Cloth —

To all to whom these presents shall come: Be it known that of Genas Bliff of Johnston in the County of Providence and State of Rhode Island have invented a new and useful improvement on Calendering cloth and the following is a full and exact description of the construction and operation of the double glazed Calendering Machine as invented or improved by me. A. B. and C. (in the drawing annexed) represent three cylinders. The cloth is received first between the cylinders A & B, it then passes between B & C and while passing between them it receives the glaze which is called the finishing; it then passes between C & D and receives another glazing —

In order to understand more perfectly the operation of the machine I will give a description of the calender now in general use. The cylinders A, B & C (in the same drawing annexed) contain all the cylinders belonging to the machine. The cylinder D is the improvement in my machine. In the common machine, ^{the cloth} enters between A & B, and going round B. comes out from between B & C. where it receives the glazing. By this process the cloth receives only a single glazing it is therefore necessary to pass the cloth twice through the cylinders in order to give it a smooth surface. Again in relation to the pressure on the necks of the cylinders; A & C. receive the whole pressure, C. making four revolutions, to A. one; consequently there is four times the friction on the necks of C to that of A. again the wear of the boxes in the machine in general use is very great. For instance a pair of composition boxes weighing 100 pounds on the necks of C. do not last more than sixty days. With all this the common machine will not average dressing the year more than two hundred pieces of cloth per day.

The improvements of my calender over the one in general use are these. The cloth receives first double the glazing and a much superior finish.

in passing through the cylinder once instead of twice in the common machine. Two pieces of cloth may pass through my machine at one and the same time and both receive precisely the same finish as one piece in the common machine. Another decided improvement relates to the pressure upon the necks of the cylinders. In my machine, A & D receive the whole pressure & move with velocity, and as D moves with one fourth less velocity than in the common machine the friction is decreased in proportion as one to four.

Another improvement, which is not only a saving of time labor, and money, is this, in the wear of the boxes, in the common machine on the necks of C, they wear out as before stated in sixty days, whereas, in my machine on the necks of D, they will last two years. As to the quantity of work performed by my machine, I am fully satisfied from experiments within my own knowledge & when I have myself superintended at my calendering establishment that said machine which has been in operation for some weeks, has performed double the amount of work, with the same water power & the same time which the common machine performed. The only additional expense is the cylinder D. and some trifling gearing in amount about one fifth extra.
